US00D688595S

(12) **United States Design Patent**
Dunn

(10) **Patent No.:** **US D688,595 S**
(45) **Date of Patent:** ** *Aug. 27, 2013

(54) **OVAL DISPLAY HOLDER FOR A CORD**

(76) Inventor: **Scott Eben Dunn**, Atlanta, GA (US)

(*) Notice: This patent is subject to a terminal disclaimer.

(**) Term: **14 Years**

(21) Appl. No.: **29/411,309**

(22) Filed: **Jan. 19, 2012**

(51) **LOC (9) Cl.** **11-02**

(52) **U.S. Cl.**

USPC **D11/184**

(58) **Field of Classification Search**

(57) **CLAIM**

The ornamental design for an oval display holder for a cord, as shown and described.

DESCRIPTION

FIG. 1 is a front perspective view of an oval display holder for a cord of the present invention;

FIG. 2 is a front elevational view of the oval display holder for a cord of FIG. 1;

FIG. 3 is a rear elevational view of the oval display holder for a cord of FIG. 1;

FIG. 4 is a left side elevational view of the oval display holder for a cord of FIG. 1;

FIG. 5 is a right side elevational view of the oval display holder for a cord of FIG. 1;

FIG. 6 is a top elevational view of the oval display holder for a cord of FIG. 1;

FIG. 7 is a bottom elevational view of the oval display holder for a cord of FIG. 1; and,

FIG. 8 is a rear perspective view of the oval display holder for a cord of FIG. 1.

1 Claim, 6 Drawing Sheets

 U.S. Appl. No. 29/394,594, filed Jun. 18, 2011, Scott E. Dunn.
 U.S. Appl. No. 29/394,595, filed Jun. 18, 2011, Scott E. Dunn.
 U.S. Appl. No. 29/394,596, filed Jun. 18, 2011, Scott E. Dunn.
 U.S. Appl. No. 29/394,597, filed Jun. 18, 2011, Scott E. Dunn.
 U.S. Appl. No. 29/394,598, filed Jun. 18, 2011, Scott E. Dunn.
 U.S. Appl. No. 29/394,599, filed Jun. 18, 2011, Scott E. Dunn.
 U.S. Appl. No. 29/394,600, filed Jun. 18, 2011, Scott E. Dunn.
 U.S. Appl. No. 29/411,277, filed Jan. 19, 2012, Scott E. Dunn.
 U.S. Appl. No. 29/411,282, filed Jan. 19, 2012, Scott E. Dunn.
 U.S. Appl. No. 29/411,283, filed Jan. 19, 2012, Scott E. Dunn.
 U.S. Appl. No. 29/411,284, filed Jan. 19, 2012, Scott E. Dunn.
 U.S. Appl. No. 29/411,285, filed Jan. 19, 2012, Scott E. Dunn.
 U.S. Appl. No. 29/411,286, filed Jan. 19, 2012, Scott E. Dunn.
 U.S. Appl. No. 29/411,288, filed Jan. 19, 2012, Scott E. Dunn.
 U.S. Appl. No. 29/411,291, filed Jan. 19, 2012, Scott E. Dunn.
 U.S. Appl. No. 29/411,293, filed Jan. 19, 2012, Scott E. Dunn.
 U.S. Appl. No. 29/411,295, filed Jan. 19, 2012, Scott E. Dunn.
 U.S. Appl. No. 29/411,296, filed Jan. 19, 2012, Scott E. Dunn.
 U.S. Appl. No. 29/411,297, filed Jan. 19, 2012, Scott E. Dunn.
 U.S. Appl. No. 29/411,298, filed Jan. 19, 2012, Scott E. Dunn.
 U.S. Appl. No. 29/411,300, filed Jan. 19, 2012, Scott E. Dunn.
 U.S. Appl. No. 29/411,302, filed Jan. 19, 2012, Dunn.
 U.S. Appl. No. 29/411,311, filed Jan. 19, 2012, Scott E. Dunn.
 U.S. Appl. No. 29/411,313, filed Jan. 19, 2012, Scott E. Dunn.
 U.S. Appl. No. 29/411,315, filed Jan. 19, 2012, Scott E. Dunn.

Specification, Claims, and Drawings entered by the U.S. Patent and Trademark Office on Jan. 19, 2012 for U.S. Appl. No. 29/411,291, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,293, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,295, filed Jan. 19, 2012 (First Named Inventor—Dunn) (7 pages).

Notice of Allowance entered by the U.S. Patent and Trademark Office on Apr. 4, 2012 for U.S. Appl. No. 29/411,295, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,296, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,297, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,298, filed Jan. 19, 2012 (First Named Inventor—Dunn) (7 pages).

Specification, Claims, and Drawings entered by the U.S. Patent and Trademark Office on Jan. 19, 2012 for U.S. Appl. No. 29/411,300, filed Jan. 19, 2012 (First Named Inventor—Dunn) (8 pages).

Specification, Claims, and Drawings entered by the U.S. Patent and Trademark Office on Jan. 19, 2012 for U.S. Appl. No. 29/411,302, filed Jan. 19, 2012 (First Named Inventor—Dunn) (8 pages).

Specification, Claims, and Drawings entered by the U.S. Patent and Trademark Office on Jan. 19, 2012 for U.S. Appl. No. 29/411,311, filed Jan. 19, 2012 (First Named Inventor—Dunn) (8 pages).

Specification, Claims, and Drawings entered by the U.S. Patent and Trademark Office on Jan. 19, 2012 for U.S. Appl. No. 29/411,313, filed Jan. 19, 2012 (First Named Inventor—Dunn) (8 pages).

Specification, Claims, and Drawings entered by the U.S. Patent and Trademark Office on Jan. 19, 2012 for U.S. Appl. No. 29/411,315, filed Jan. 19, 2012 (First Named Inventor—Dunn) (8 pages).

Specification, Claims, and Drawings entered by the U.S. Patent and Trademark Office on Jan. 19, 2012 for U.S. Appl. No. 29/411,316, filed Jan. 19, 2012 (First Named Inventor—Dunn) (8 pages).
